ATTORNEYS.

UNITED STATES PATENT OFFICE.

JOSEPH HERRBURGER, OF PARIS, FRANCE.

PIANO-ACTION.

SPECIFICATION forming part of Letters Patent No. 471,717, dated March 29, 1892.

Application filed June 5, 1891. Serial No. 395,181. (No model.)

To all whom it may concern:

Be it known that I, JOSEPH HERRBURGER, of Paris, France, have invented an Improved Piano-Action, of which the following is a specification.

This invention relates to a repeating-action for upright pianos of the kind in which the fixed back-check is dispensed with and supplanted by a back-check secured to and moving with the hammer-butt.

The invention consists in the various features of improvement more fully pointed out in the claim.

In the accompanying drawings, Figure 1 is an elevation of my improved action with the key raised; Fig. 2, a similar elevation with the key depressed, and Fig. 3 a detail of the hook *e*.

The letter *a* represents the key of an upright-piano-forte action. *b* is the lever, *c* the jack, and *d* the hammer-butt. The butt *d* is provided with a padded notch *d'*, that is engaged by a rearwardly-projecting nose *c'* of the jack. Opposite said nose the jack *c* is provided with an upwardly and forwardly extending head *c²*, having a straight padded front edge *c³*. The upper edge *c⁴* of head *c²* is slanting, extending downward from the edge *c³* to the nose *c'*, so that thus the edge *c³* projects a considerable distance farther up than the nose *c'*, as shown.

To the hammer-butt *d* there is secured the shank of a hook *e*, the head *e'* of which is straight from top to bottom and is in line with the edge *c³* when the key is depressed, 35 Fig. 2. This head *e'* of the hook is flattened laterally, as shown, so as to afford a firm and wide bearing for the jack. When the key is depressed, the nose *c'* will throw the hammer against the string, and will then partly slip 40 out of the notch *d'* to permit the hammer to fall away from the string. This motion is continued until the edge *c³* comes into contact with the head *e'* of the hook *e*, when the jack will serve as a back-check. A slight release of the key *a* will now cause the jack to come clear of the hook, so that the nose *c'* is reintroduced into the notch *d'*, ready for the next depression of the key. In this way a 45 very sensitive repeating-action is produced. 50

What I claim is—

The combination of a jack having a rearwardly-projecting nose *c'* and a forwardly-projecting head *c²*, that extends above the nose, with a mortised hammer-butt, and a 55 hook secured thereto, substantially as specified.

JOSEPH HERRBURGER.
